US00D994427S

(12) **United States Design Patent** (10) **Patent No.:** **US D994,427 S**
Huang (45) **Date of Patent:** **** Aug. 8, 2023**

(54) **KNIFE HANDLE**

(71) Applicant: **Yangjiang LIYANG E-Commerce Co., Ltd.**, Guangdong (CN)

(72) Inventor: **Shuyan Huang**, Guangdong (CN)

(73) Assignee: **Yangjiang LIYANG E-Commerce Co., Ltd.**, Guangdong (CN)

(**) Term: **15 Years**

(21) Appl. No.: **29/796,017**

(22) Filed: **Jun. 22, 2021**

(51) LOC (14) Cl. **07-06**

(52) U.S. Cl. **D7/401.2; D22/118**

(58) **Field of Classification Search**

USPC **D7/401.2, 368, 393-395, 642-646, D7/649-654, 660-664, 688-692, D7/695-696; D8/25, 83, 99, 107, 303;**

D22/18

CPC .. **B26B 27/00; B26B 3/06; B26B 3/03; B26B 3/02; B26B 9/00; B25G 1/102**

(57) **CLAIM**

The ornamental design for a knife handle, as shown and described.

DESCRIPTION

FIG. 1 is a front and top perspective view of a knife handle, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict environmental subject matter that form no part of the claimed design.

1 Claim, 8 Drawing Sheets
